UNITED STATES PATENT OFFICE.

GEORGE ZINT, OF WAPAKONETA, OHIO.

COUPLING.

1,193,658.

Specification of Letters Patent.

Patented Aug. 8, 1916.

Application filed April 12, 1915. Serial No. 20,898.

To all whom it may concern:

Be it known that I, GEORGE ZINT, a citizen of the United States, residing at Wapakoneta, in the county of Auglaize and State 5 of Ohio, have invented certain new and useful Improvements in Couplings; and I do declare the following to be a full, clear, and exact description of the invention, such as will enable others skilled in the art to which 10 it appertains to make and use the same.

This invention relates to improvements in couplings especially adapted for use in connection with automatic sprinklers and more particularly to the sprinkler shown in my 15 Patent Number 1,146,228 dated July 13, 1915.

The object of the invention is to provide simple and efficient means for connecting and permitting a sprinkler nozzle or head 20 to swing laterally relative to the pipe with which it is connected.

With this and other objects in view, the invention consists of certain novel features of construction, and the combination and 25 arrangement of parts as will be more fully described and claimed.

In the accompanying drawings: Figure 1 is a longitudinal vertical section taken through a nozzle and the pipe with which 30 it is connected showing this improved coupling applied; Fig. 2 is a transverse vertical section taken on the line 2—2 of Fig. 1; Fig. 3 is a detail perspective view of the nozzle detached.

35 In the embodiment illustrated a table 5 is shown revolvably mounted on a casting 6. This table 5 is mounted similarly to the bracket 17 in the patent above referred to and is adapted to be revolved by means similar 40 to that shown in said patent, comprising a large worm gear 15 actuated by means not shown, so that when said worm gear is turned the table 5 and all of the parts carried thereby are revolved. This casting 6 45 as here shown, has a laterally extending tubular arm 10 provided at its outer end with an upward extension 11 which terminates in a laterally extending socket 12, said socket being here shown arranged parallel 50 with the arm 10 and in a plane above it.

The casting 6 which carries the nozzle 9, is held against turning relatively to the table 5 by means of a socket 13 depending from the lower face of the arm 10 and positioned to removably engage the upper end 55 of a post 14 which is fixed to and extends

upwardly from said table at a suitable point to engage the socket 13. The socket or female member 12 of the coupling is externally threaded and is provided on its inner 60 face at a point spaced inwardly from its free end, with an annular shoulder or flange 15 having a notch 16 formed therein for a purpose now to be described.

The nozzle 9, which is connected with the 65 socket 12, has a tubular extension or male member 17 which is provided with a laterally extending lug 18 of a width slightly less than the width of the notch 16 in the flange 15, to provide for the ready passage 70 of this lug through said notch when the parts are assembled. As shown, this tubular extension has a shoulder 19' at its inner end or base which is designed to abut against the outer face of the flange 15 when the parts 75 are assembled to limit the inward insertion of the nozzle in the socket. The larger cylindrical shank portion of the nozzle terminates at its inner or rear end, in a shoulder 21 against which a clamping nut 22' is de- 80 signed to abut when the parts are assembled and the nozzle held in adjusted position by said nut. This adjustable locking and packing nut 22' is internally threaded and of a size to fit the threaded outer face 85 of the socket 12, said internally threaded bore of said nut terminating about midway the ends of the nut and having an annular shoulder at its inner end, which is designed as a stop for limiting the inward movement 90 of said nut on said socket 12, the bore of the shouldered portion thereof being unthreaded and corresponding in diameter to the internal diameter of the socket 12 to permit the nozzle 9 to be readily inserted 95 through said nut into said socket while the nut is already in engagement with the socket. The unthreaded shouldered portion of the nut 22' as shown is formed by the insertion in the nut of a suitable packing 23' 100 to insure a water tight connection of said nut with the nozzle. This packing 23' is arranged between an inturned annular flange 23'' formed on the outer end of the nut and the inner end of the threaded portion of said nut.

The larger portion of the male member 17 at the rear of the shoulder 21 thereof, corresponds in diameter to the diameter of the unthreaded portion of the nut and of the 110 socket 12, or is slightly less in diameter so as to provide for its insertion in said mem-

bers and its ready turning therein when it has been so inserted. Any suitable packing means may be provided between the nut 22, the socket 12, and nozzle 9, to form a water 5 tight connection between these parts to prevent leaking during the operation of the sprinkler. A coiled spring 12' is shown mounted in the member 12 between a shoulder 12^a and the rear end of the member 17 10 and exerts its tension to assist in holding the nozzle yieldably in fixed position.

In the use of this improved coupling, it is obvious that any form of nozzle may be employed in connection with the socket 12 15 provided the stem or shank of said nozzle be equipped with the lug 18 and the shoulders 19' and 21 above described, and to assemble the nozzle or connection with the socket 12, the lug 18 carried by the stem or shank of the nozzle must be placed in alignment with the notch 16 in the flange 15 of said socket, so that when said nozzle is moved inwardly this lug will pass through the notch 16 to the rear face of the flange 15 20 and on the turning of said nozzle shank this lug will engage the rear face of the flange 15 and thus lock the nozzle against removal until the lug is again brought into register with the notch 16. It will thus be obvious 25 that when this nozzle is so connected that the shank thereof may rotate freely in the socket 12 and swing in a vertical plane when the parts are positioned as shown in the accompanying drawings, said nozzle swinging 30 laterally relative to the socket 12, no matter in what position it may be placed. When the nozzle has been positioned as desired, it is held in adjusted position by turning the nut 22' outward until it abuts 35 against the shoulder at the base or inner end of the nozzle shank, and the continued outward turning of said nut forces the nozzle away from the socket 12 causing the lug 18 thereof to bindingly engage the inner 40 face of the flange 15 and thus securely lock the nozzle 9 in adjusted position relatively to the socket 12. It will thus be seen that the position of this nozzle 9 may be changed when desired so as to vary the sprinkling 45 of the water discharged therefrom.

I claim as my invention:—

A coupling comprising a socket member

with its terminal exteriorly threaded, an annular shoulder formed at the base of said threaded portion on its inner face and having a notch therein, said member having an annular recess at the rear of said shoulder, the rear wall of said recess extending laterally into the socket member beyond the free edge of the shoulder thereof to form a 60 spring supporting seat, a coöperating male member having a reduced free end to extend through the shouldered portion of the socket member and having an external shoulder formed at the base of said reduced 65 portion and adapted for abutting engagement with the shoulder of the socket member, the body portion of said male member at the rear of its shoulder fitting within the socket member in advance of the shoulder 70 thereof, an annular flange formed on said male member at a point spaced rearwardly from its shoulder, a laterally extending lug on the reduced portion of said male member for insertion through a notch in the shoulder of the socket member, an adjustable internally threaded locking and packing nut of a size to fit the threaded outer end of the socket member, the threads of said nut terminating about midway the ends thereof, a 75 shoulder extending laterally inward from said nut at the inner end of the threaded portion thereof to form a stop for engaging the end of the threaded portion of the socket member for limiting the inward movement 80 of said nut on said socket member, the bore of said nut beyond the shoulder thereof being unthreaded and corresponding in diameter to the internal diameter of the socket member to permit the body portion of the 85 male member to be readily inserted therethrough and to enter the socket member while the nut is in engagement therewith, and a coil spring mounted on the seat in said socket member between it and the free 90 end of the male member.

In testimony whereof I have hereunto set my hand in presence of two subscribing witnesses.

GEORGE ZINT.
